Primary Examiner—Ruth McInroy

(57) **CLAIM**

The ornamental design for a vacuum head attachment for air-activated vacuum cleaners, as shown and described.

DESCRIPTION

FIG. 1 is a front elevational view of a vacuum head attachment for air-activated vacuum cleaners showing my new design;

FIG. 2 is a rear elevational view thereof;

FIG. 3 is a right side elevational view thereof;

FIG. 4 is a top plan view thereof;

FIG. 5 is a bottom plan view thereof; and,

FIG. 6 is a perspective plan view thereof.
